UNITED STATES PATENT OFFICE.

LUCIUS J. RICHARDS, OF PHILADELPHIA, PENNSYLVANIA.

DESIGN FOR A COFFEE OR TEA POT.

SPECIFICATION forming part of Design No. 18,355, dated May 29, 1888.

Application filed April 11, 1888. Serial No. 270,374. Term of patent 14 years.

To all whom it may concern:

Be it known that I, LUCIUS J. RICHARDS, a citizen of the United States, residing in the city and county of Philadelphia, State of Pennsylvania, have invented and produced a new and original Design for Coffee or Tea Pots, of which the following is a specification, reference being had to the accompanying drawing, forming part thereof.

10 The figure represents a partial vertical section and partial side elevation of a coffee or tea pot embodying my design.

15 The leading features of my design consist of the base portion of the body, of the form of a prolate spheroid, the bottom with the segment of a sphere in the center thereof, a cylindrical top portion, and a handle connected with said top and bottom.

20 A represents the body of a coffee or tea pot, the top portion, B, whereof is a cylinder, and the base portion, C, is a prolate spheroid.

D represents the segment of a sphere on the

bottom, E the spout, and F the handle, the latter being connected with the cylindrical top and spheroidal base and extending in oblique direction. 25

G represents the lid or cover of the pot.
I claim—

1. In a design for a coffee or tea pot, a body having its base portion of the form of a prolate spheroid, with a segmental spheroid in the bottom thereof, substantially as shown and described. 30

2. The design for a coffee or tea pot, consisting of a body with the base portion of the form of a prolate spheroid, the bottom thereof having a central segmental spheroid, and the top of the body being of cylindrical form, substantially as shown and described. 35

LUCIUS J. RICHARDS.
